FIG. 1

FIG. 2

FIG. 3

FIG. 4

FIG. 5

FIG. 1 is a top view of a hand magnifier showing our new design;

FIG. 2 is a side view of said magnifier;

FIG. 3 is a bottom view of said magnifier;

FIG. 4 is an end view taken from the right side of said magnifier as viewed in FIGS. 1-3; and

FIG. 5 is an end view taken from the left side of the hand magnifier as viewed in FIGS. 1-3.

The side not shown has substantially the same appearance as the side shown.

The characteristic feature of our design resides in the handle portion of the magnifier as shown.

We claim:

The ornamental design for a hand magnifier, substantially as shown and described.
